Des. 185,796
Patented Aug. 4, 1959

185,796

RELIGIOUS VESTMENT HOLDER OR SIMILAR ARTICLE

Boles Liubauskas, Du Bois, Pa.

Application April 1, 1958, Serial No. 50,277

Term of patent 14 years

(Cl. D17—8)

Fig. 1.

Fig. 2.

Fig. 3.

I claim:

The ornamental design for a religious vestment holder or similar article, as shown.
